UNITED STATES PATENT OFFICE.

WILLIAM M. WILKIN, OF ERIE, PENNSYLVANIA.

GANG-SAW MILL.

SPECIFICATION forming part of Letters Patent No. 380,236, dated March 27, 1888.

Application filed October 13, 1887. Serial No. 252,194. (No model.)

To all whom it may concern:

Be it known that I, WILLIAM M. WILKIN, a citizen of the United States, residing at Erie, in the county of Erie and State of Pennsylvania, have invented certain new and useful Improvements in Gang-Saw Mills; and I do hereby declare the following to be a full, clear, and exact description of the invention, such as will enable others skilled in the art to which it appertains to make and use the same.

This invention relates to gang-saw mills; and it consists in certain improvements in the construction and operation thereof, as will be hereinafter fully set forth, and pointed out in the claims.

My invention is illustrated in the accompanying drawings, as follows:

Figure 1 is a front elevation of a gang-saw mill with my improvements thereon, only so much of the mill being shown as is necessary to fully illustrate the application of my improvement. Fig. 2 is a vertical section on the line *xx* in Fig. 1, the parts being drawn on a larger scale, and only such parts being shown as are necessary to illustrate my improvement. Fig. 3 is a view like that in Fig. 1, on an enlarged scale, showing only such parts as are necessary to illustrate my invention and showing an alternative construction.

Specifically speaking, my improvements relate to means for moving the saw-frame, and in no way relate to the general construction of the mill, but are applicable to mills of various construction, as to frame-work, feed-rollers, &c. Only such of the various parts of the mill will be referred to as are necessary to explain the relation of such parts as are new.

A marks the frame-work of the mill, and B the saw sash or frame; D, the crank-shaft; D' and D²D², the cranks on said shaft, and D³ the balance-wheels.

In all gang-saw mills with which I am acquainted the power is either applied to drive the crank-shaft, and from it the saw-sash is driven, or else the power is applied directly to the saw-frame, and from it the crank-shaft is driven by proper connecting-rods. In the latter instance the crank-shaft is merely used to operate proper balance-wheels and operate the valve-gear. Heretofore in every instance, so far as I am aware, swinging con-

necting-rods are used between the crank-shaft and the saw-sash. One of the objects of my constructions is to avoid the use of such connecting-rods, because in the rapid movement of the mill the rapid vibratory movement of the connecting-rods, as the crank revolves, generates a lateral vibration in the framework, and, further, because they give to the saw-frame a lateral thrust, first on one side, then on the other, causing considerable friction on its guides. To accomplish this result, I provide at the lower part of the frame a steam-engine cylinder, (marked G in Figs. 1 and 2, and G' in Fig. 3,) and the piston-stem from this cylinder (or one of them where there are two stems, as shown in Figs. 1 and 2) extends up and takes hold of the saw-frame B at *b*. This stem is marked C in the drawings. In this stem C, at the point where it takes hold of the middle crank, D', of the crank-shaft, there is provided a yoke with a horizontal slot-opening, and in this slot the journal-boxes of the wrist-couplings, which engage the wrist-pin of that crank, are secured and slide horizontally as the crank-shaft revolves.

The reciprocating action of the piston of the steam-cylinder reciprocates the saw-frame by direct action, and it generates a rotary action of the crank-shaft by reason of the slot or yoke in the stem. The only lateral throw there is is that of the cranks and the journal-boxes, and, as the cranks of the crank-shaft will be properly balanced, this will produce no lateral vibration perceptible.

In the construction shown in all the figures I provide for balancing the saw-frame by a reciprocating counter-balance E. In the construction shown in Figs. 1 and 2, the steam-cylinder has two pistons which move in opposite directions, Fig. 1 showing them in extreme separation, and Fig. 2 in extreme approximation. These pistons are marked H and H', the former being connected with the stem C, and the latter with a stem, F, which extends from the lower end of the piston and connects directly with the weight E. Rods E'E', having yokes E²E², are connected with the weight E and cranks D²D², and are guided in guides at *e e' e'*. These rods have only a vertical movement and no lateral movement whatever. They serve to transmit to the

crank-shaft and thence to the saw-frame the power exerted by the steam upon the piston H'. The weight of these rods, the weight E, the stem F, and piston H' will be proportioned 5 so as to be equal to the weight of the saw-sash, the stem C, and piston H, or substantially so.

As before stated, it will be seen there is no lateral movement of the parts except the cranks, and there is no lateral thrust by the 10 connecting parts upon the frame, and hence lateral vibration and friction are avoided.

In the construction shown in Fig. 3 the steam-cylinder G' has but one piston and piston-stem, and this takes hold of the saw-frame, 15 and the counter-weight E is moved by the crank-shaft. In this figure the weight is shown as guided in guides I; but this is not material, for it may be guided by guides on the rods E', as in Fig. 1.

20 What I claim as new is —

1. In a gang-saw mill, the combination, substantially as set forth, of a reciprocating saw-frame, a steam-engine cylinder having a reciprocating piston, a stem or rod connecting said piston directly with said frame, a horizontal slot or yoke in said rod or stem, a journal-box sliding in said yoke or frame, and a crank-shaft having one of its crank-pins embraced by said sliding box.
2. In a gang-saw mill, the combination, substantially as set forth, of a reciprocating saw-frame and a reciprocating counter-balance, a steam-engine cylinder having a reciprocating piston, a rod or stem connecting said piston directly with said saw-frame, a horizontal slot or yoke in said rod or stem, which receives the journal-box of a crank-pin, and a crank-shaft having three cranks, the middle one of which stands opposite the other two and has its pin 35 journaled in said journal-box, and rods con-

necting the other two cranks with the said counter-weight.

3. In a gang saw mill, the combination, substantially as set forth, of a reciprocating saw-frame, a reciprocating counter-weight, a steam-engine cylinder having a reciprocating piston, a crank-shaft having three cranks, as shown, a rod or stem connecting said piston directly with said frame, a horizontal yoke or slot in said rod or stem, which receives the journal-box of the middle crank of said crank-shaft, and two vertically-guided rods which connect with said counter-weight and are provided with yokes or slots, the same as said piston-stem, which receive the journal-boxes of the 55 outer cranks of said crank-shaft.

4. In a gang-saw mill, the combination, substantially as set forth, of a reciprocating saw-frame, a reciprocating counter-weight, a steam-engine cylinder having two pistons which reciprocate in opposite directions, a rod or stem connecting one of said pistons with the said counter-weight, and a rod or stem which connects the other of said pistons with the said saw-frame, a crank-shaft having three cranks, 60 the middle one of which is opposite the other two, a slot or yoke in the piston-stem, which connects with the saw-frame and embraces the journal-box of the middle crank, and two vertically-guided rods which connect with said 65 counter-weight and are provided with yokes or slots, the same as in the said piston-stem, which receive the journal-boxes of the outer cranks of said crank-shaft.

In testimony whereof I affix my signature in 70 presence of two witnesses.

WILLIAM M. WILKIN.
